UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed November 4, 1921. Serial No. 512,741.

To all whom it may concern:

Be it known that I, JOHN WALDHEIM, a citizen of the United States, residing in Elizabeth, in the county of Union and State of New Jersey, have invented certain new and useful Improvements in Typewriting Machines, of which the following is a specification.

The present invention relates to certain features of a typewriting machine to adapt the same to a sound-deadening casing in which the machine may be operated; and to certain features of the casing for better adaptation of the same to operation of the machine therein.

Casings of this character have heretofore been provided with windows, for rendering visible the printing effected within the same. It has been found that light, either artificial light or sunlight, striking the window-pane at certain angles, is objectionably reflected into the eyes of the operator.

One object of the present invention is the provision of means whereby the window-pane may be angularly adjusted to divert such reflection.

It is common knowledge that reflection is intensified or softened, according to the density of shadow of the background. Heretofore, the casings have been opaque, except for the forementioned window, thus enhancing reflection of light from the window-pane.

An object of the present invention is the provision of windows at the ends of, or elsewhere in, the casing, to admit light to the interior thereof beyond the window, through which the operator observes the platen; thus eliminating, to a large degree, all objectionable reflections from the window-pane, through which the operator looks.

It is desirable to adapt the casing to use with the machine on the usual folding or collapsible desk-board. Heretofore, the casings have been provided with covers, hinged thereto at the rear, and have been provided with springs for assisting in the opening of the cover; the cover being held down against the action of such springs by gravity. As the casing is tilted with the machine, in the operation of folding the same into the desk, on arriving at a certain position, gravity may cease to be effective to hold the cover in place, and the latter, urged by its springs, or by gravity, may swing open.

An object of the present invention is the provision of means for locking the cover to the casing-body, which means may be rendered ineffective during the operation of the machine, so that the cover may be opened 60 at will, and which may be readily, and in a simple manner, rendered effective when the casing is to be folded into the desk, or otherwise tilted.

Casings of the character mentioned ordinarily have a slot extending horizontally across the front face thereof, through which protrude the operating arms, such as the line-space lever, the carriage-release-lever, and the carriage-return arm, and along 70 which these arms travel with the carriage. These arms and the machine and the casing all being standardized, all of these arms on a given machine should register with the slot in any casing designed to receive such 75 machine; and, vice versa, the slot in a given casing should be in registry with all of such arms on any machine intended for such casing. Lack of uniformity, such, for instance, as may be due to wear of, or injury 80 to, the feet of the typewriting machine, or bending of the arms, may result in occasions where one or all of the arms do not register with the casing-slot. In such instances, the arm will bind or unduly bear upon one or 85 the other wall of the slot, and freedom of movement be thus impaired. A comparatively light pressure of the line-space-lever or the carriage-release-lever, for example, may be sufficient to prevent return of the 90 same, after their operation, to normal position, by the springs designed for this purpose; or such pressure of any of these arms or levers on the walls of the slot may prevent the proper letter-feed movement of the carriage by the spring-drum. 95

Another object of the invention is the provision of means whereby these arms or levers may have vertical play, so as to accommodate themselves to the slot along 100 which they travel, regardless of any defect or lack of uniformity in any part of the casing or machine. It is a further object of the invention to provide for this play without in any way impairing the accuracy 105 of operation of the levers. In connection with the line-space-lever, for instance, a feature of the invention is the provision of means whereby this play is provided without producing looseness or play in the hori- 110

zontal plane in which the lever has its normal operation.

In typewriting machines, whether or not for operation within the casing, but more particularly for operation within the casing, the carriage-release-lever has been mounted upon the carriage-return-arm, or in such proximity thereto as to permit the finger-pieces of both to be engaged by one hand, so that the carriage-release-lever may be pinched toward the carriage-return-arm in the operation thereof. This pinching is best effected by engaging the carriage-return-lever with the thumb in horizontal position, and the carriage-release-lever with the forefinger in vertical position.

A feature of the invention is a vertical placement or disposition of the finger-piece of the carriage-return-arm, and a horizontal placement or disposition of the finger-piece of the carriage-release-lever; the finger-pieces thus being at right angles to each other, as are the thumb and forefinger by which they are engaged, and being in the positions naturally adapting the same for engagement and operation by the hand.

Other features and advantages will hereinafter appear.

In the accompanying drawings,

30 Figure 1 is a view, in side elevation, of the assembled machine and casing, the casing being in cross-section and broken away, to show certain features of the machine and casing.

35 Figure 2 is a cross-sectional view, in side elevation, through the top of the casing, to illustrate a mounting of the window-pane.

Figure 3 is a view similar to Figure 2, showing a different adjustment of the window-pane.

Figure 4 is a front view of the cover, broken away and partly in cross-section, to show certain details thereof.

45 Figure 5 is a perspective view of the line-space-lever, the handle being broken away.

Figure 6 is a front view, in cross-section, of the line-space-lever and the carriage-bar on which it is mounted.

50 Figure 7 is a side view, partly in cross-section, of the part shown in Figure 6.

Figure 8 is a top plan view of the carriage-return-arm, the carriage-release-lever, and certain connections to the same.

55 Figure 9 is a view, in side elevation, of the carriage-return-arm; the connections of the same to the carriage front rail being shown in cross-section.

Figure 10 is a side view, in cross-section, through the carriage-release-lever, and 60 through the connections of the same to the carriage front rail.

65 The casing is shown as comprising two principal castings, one of which 10 constitutes the body of the casing, and the other of which 11 constitutes a cover hinged at 12

to the body-portion. As indicated at 13, the body-portion is lined with a sound-deadening material, such, for instance, as felt; and, as indicated at 14, the cover is similarly lined. The body-portion of the casing is 70 shown as having a floor or bottom 15, secured to the casting of the casing-body in any suitable manner; and the casing, as a whole, rests upon a platform or drop leaf 16, which may be folded or collapsed into a 75 typewriter desk in the usual manner.

The main frame 17 of the typewriting machine, indicated in dotted lines in Figure 1, is supported by front and rear feet 18 and 19. The keyboard-extension 20 of the 80 typewriting machine projects through a suitable opening in the front wall of the casing, and suitable sound-deadening linings (not shown) are provided at the front of the casing. The typewriting machine is 85 shown as anchored by bolts 21 in much the usual way to the platform 16. The platform 16 and felt bottom of the casing are perforated for loose passage therethrough of the bolts 21; and, to prevent emission of 90 sound through the bolt-openings, washers 22, of felt or other sound-proof material, are inserted under the heads 23 of the bolts. The bolts 21 thread into the usual lugs 24 on the frame 17 of the typewriter. In the 95 present instance, the casing, not being liftable independently of the typewriting machine, is therefore indirectly held to the platform 16 by the bolts 21.

For assisting in the opening of the casing-cover, there is provided, at each side of the casing, a spring (not shown), concealed within a cylinder 25, which spring bears at one end against one end of its cylinder, and at its other end against a piston on a rod 26. 100 The rod 26 is secured at 27 to the casing-cover; and the cylinder, in which it slides, is secured at 28 to the casing-body. Brackets 29 and 30 attached, respectively, to the cover and the casing-body, serve as anchors 110 for the rods 26 and cylinders 25, respectively. Metal strips 31, 32, laid against the inside of the edges of the linings 13 and 14, respectively, and running longitudinally of such lining-edges, are secured to the body 115 and over castings by screws 33, and thus serve to hold the linings at their edges.

Normally, gravity suffices to hold the cover closed; in which position (see Figure 4) the lining-strips 14 at the sides of the 120 cover rest upon the casting 10 of the body-part. Ribs 35, formed in the side or end walls of the cover-casting, serve as reinforcements therefor, and as abutments for the lining-strips 14. When the casing with 125 the machine is folded back into the desk a sufficient distance, gravity may no longer serve to hold the cover to its seat on the casing-body; and, at such times, to hold the cover to the casing-body, a lock or detent 130

is provided. This lock or detent (see Figures 1 and 4) consists of a spring-arm 37, pivoted at 38 to the casing-cover, to have movement thereon to the full and dotted line 5 positions of Figure 1. The distal end of the spring-arm 37 carries a bolt or lock-pin 39. Normally, that is to say, when the machine is in position for operation, and when it may be desired to open the cover, for any 10 purpose, the arm 37 is in the full line, Figure 1, position, sprung or bent out, with the pin or bolt 39 centered and resting in a recess 40, also in the cover end wall. Before the machine and casing are folded back into 15 the desk, however, the arm 37 is swung to the dotted line, Figure 1, position, at which time, the bolt 39 is brought into registration with a hole 41, which passes entirely through the end wall of the cover, and 20 which hole 41 is in registration with a hole 42 in the end wall of the casing-body. At this time, the spring-action of the arm 37 causes the bolt 39 to enter the holes 41 and 42, thereby locking the cover against movement on its hinge 12.

In the forward upper part of the cover, is a window, formed by a rectangular ribbing 45 in the cover-casting. This ribbing has the function of a reinforcement for the 30 cover, and also serves, as indicated at 46 in Figure 1, as an abutment for the cover-lining-member. Within the window, formed by the ribbing 45, is a window-pane 47, of glass or other transparent material. At 35 either end, the window-pane 47 is perforated to receive screws or rivets 48, by means of which it is attached to, and supported upon, the flanges 49 of brackets 50. The brackets 50 are pivotally secured to the ribbing 45 of the cover-casting by means of 40 pins or screws 51 (see Figures 1 and 4). Upon loosening the screws 51, the pane 47 may be set at any angle within its frame, and, upon tightening the screws 51, will be 45 held at the angle at which it is so set. By adjusting the angle of the window-pane in this manner, any undesirable reflection of daylight or artificial light may be turned from the operator's eyes. A lining 53, of 50 felt, leather, or other sound-deadening material, is secured by screws 54 to the ribbing 45. The window-pane 47 is slightly wider, fore and aft, than the frame formed by the felt 53; and the edges of the pane are rounded, as at 55, so that, in adjusting the pane, the edges thereof may be moved along and held by the yieldable lining 53.

Figures 2 and 3 show a modified form of 55 adjustable window-pane. In the structure shown in these figures, the ribbing 45 is provided, at the outer face of the cover, with a peripheral flange 56, against which the front or rear edge of the window-pane is adapted to be set. The window-pane is 60 of greater width, fore and aft, than the frame formed by the ribbing, and so is set diagonally in its frame. It is held in its frame by clamps, consisting of fingers 57, secured to the inner face of the ribbing by screws 58. These clamps are disposed in 70 various positions around the window-pane, on the front and rear thereof. Spacing-strips 59, of wood or other material, bear against the front and rear edges of the window-pane. In Figure 2, the strip 59, at 75 the rear of the window-frame, lies between the window-pane and the clamp 57, and holds that edge of the window-pane tightly against the flange 56 of the ribbing. The strip 59, at the front of the window-frame, in Figure 2, on the other hand, lies between the window-pane and the flange 56 of the ribbing, thereby holding the front edge of the window-pane tightly against the clamp 57. The strips 59 are preferably bound by 80 felt or like shock-absorbing strips of yieldable material 60. It is designed that, after the pane 47 and the strips 59 are in place, the clamps may be tightened against the yieldable bindings 60, and the window-pane 85 thereby so held in its frame that all joints are closed and rendered sound-proof. The arrangement shown in Figure 2 is transformed into the arrangement shown in Figure 3 by loosening the clamps, taking out the window-pane and the strips 59; positioning the rear strip 59 against the flange 56; setting the window-pane in, with its front edge against the flange 56, and its rear edge 90 against the strip 59; positioning the front strip 59; and applying the clamps. This simple operation, it will be noted, has entirely changed the angle of the window-pane; and any previous objectionable reflection of light has thereby been diverted from 95 the operator's eyes.

Any objectionable reflection from the top window-pane 47 is intensified by darkness of the interior of the casing. This darkness may, however, be relieved by windows in the end walls of the cover or elsewhere. As shown in Figures 1 and 4, the cover end wall consists of a peripheral flange 65, forming a window-frame, in which is seated a pane 66, of glass or other transparent or translucent material. Each window-pane 66 is set against a smaller peripheral flange 67 on the window-frame 65; and clamps 68, similar to the clamps 57, are disposed around the inside of the window-frame, to hold the window-panses 66 to their seats. Suitable sound-deadening and shock-absorbing strips 69 are positioned between the window-panses 66 and their seats 67. The clamps 68 are held to the inside faces of the flanges or ribs 65, forming the ends of the casing-cover.

The typewriter-carriage 70 is mounted to have letter-feed and return movement on a rear rail 71 and a front rail (not shown) 72 on the typewriting machine. The platen 73

is mounted for rotary movement in the platen-frame 73 on the carriage. The carriage is driven by the usual spring-drum and is controlled by a pinion (not shown), which meshes with a rack (not shown) on the carriage. To release the carriage from such control, the rack referred to is liftable out of engagement with the pinion, a lever 74 being provided for this purpose. The carriage-controlling and release connections, just mentioned, are those found in the Underwood standard typewriting machine. The line-space mechanism of the Underwood machine comprises a ratchet-wheel (not shown) on the platen-shaft, and a pawl (not shown), for engagement with the ratchet-wheel; the pawl being mounted on a slide 75 for reciprocatory movement. For operating the pawl, there is provided a bell-crank-lever, having pivotal movement in a horizontal plane on a pivot-pin 76 on the carriage-frame. One arm 77 of the line-space-lever is adapted to engage and actuate the pawl-carrying slide, and the other arm 78 carries the finger-piece or handle for operating the lever. A carriage-return-arm 79 is also provided.

The carriage-release-lever, the line-space-lever and the carriage-return-arm, shown in the drawings, are not precisely of the shape and style commonly found in the standard Underwood machine. This is because the machine is here shown as adapted for operation within the sound-deadening casing, and it is desirable that the levers, referred to, be extended to the outside of the casing, whereby they are accessible to the operator. Where the levers thus protrude to the outside of the casing, the casing must be slotted, to permit of movement of the levers, along the front thereof, with the carriage as the carriage has letter-feed and return movements. In Figure 1, the several levers, referred to, are shown as extended, and bent so that all of them may protrude through a single slot. The walls of this slot are formed by two cushions 80, each of which cushion comprises an inner tubing of rubber or other resilient material 81, supported in a strip of felt 82, the ends of the felt strip being brought together and held to the inside front wall of the casing by metal strips 83, through which and the gathered ends of the felt strips 81, screws 84 pass, and are threaded into the casing front wall. The cushions are of sound-deadening material, and are resilient, so as to close the slot, except where the levers intercede.

Referring to Figures 1 and 8 of the drawings, it will be noted that, on the front rail 86 of the carriage, there is a plate 87, secured to the rail by a clamp 88 and a set-screw 89. Screws 90 and 91 hold the plate 87 and clamp 88 together. Screw 91 has a further function of serving as a pivot for

a carriage-release-lever 92, having a finger-piece 93, on one arm thereof, and having, on another arm 94, a yoke 95, which engages an upturned part 96 of the carriage-release-lever 74, heretofore referred to. Movement of the finger-piece 93 to the left causes the arm 94 to be rocked forward, and the lever 74 to be swung forward and downward; play being allowed at the yoke 95 for such downward swing of the lever 74. Referring to Figure 1, it will be noted that the lever 92, between its pivot 91 and the finger-piece 93, has a downward bend to a point opposite the line of contact of the two cushions 80, and is then offset horizontally forward.

As hereinbefore mentioned, typewriting machines of a given make and standard are supposed to be interchangeably usable in the casing, and, vice versa, casings, such as shown, are supposed to be interchangeable for a given machine. Likewise, the levers are supposed to be standardized, so that one may be replaced by another on a given machine, and so that, when thus mounted upon the machine, their horizontal offsets will be in registration with the slot formed by the cushions 80. In event of failure of an arm or lever truly to register with the slot, the pressure of one of the cushions thereon may be such as to interfere with its freedom of movement, or with the movement of the carriage. The springs for returning the lever and the carriage may not be strong enough to overcome such pressure and friction, and thus the carriage may fail to feed forward, or the lever fail to return to normal position. This condition may apply to the carriage-release-lever, to the carriage-return-arm, or to the line-space-lever; and the possibility that all three of the levers and arm will not truly register is greater than that any particular one of the same will not register. It has been stated that one of the objects of the invention is to give these levers and arm a certain flexibility vertically, so that they will adapt themselves to the line of the cushion-slot. The manner, in which this flexibility of the several levers and arm is obtained, is as follows:

Referring to Figure 10, it will be noted that the hole 100 in the carriage-release-lever 92, through which hole the pivot-pin 91 passes, and which hole forms the bearing for the lever on the pin 91, is not truly cylindrical. In the fore-and-aft cross-section shown in Figure 10, the walls of the hole 100 are shown as rounded outwardly at 101, both above and below the medial horizontal line. This rounding or tapering off of the bearing of the lever 92 on the pin 91 permits the lever to have a slight up-and-down rocking movement. If, therefore, the horizontal offset of the lever to its finger-piece 93 is not in true alignment with the slot pro-

vided by the cushions 80, pressure of the cushions will cause the lever to be rocked up or down to a position where neither cushion unduly bears upon the same.

5 Provision for the up-and-down adjustment of the carriage-return-arm is shown in Figure 9. It will be remembered that the carriage-return-arm requires no pivotal movement in a horizontal plane upon its 10 support. The carriage-return-arm 79 is shown as pivoted at 103, for up-and-down movement on an ear 104 on the plate 87. A screw 105 passes vertically through the arm 79 and into the plate 87. The opening for 15 the screw 105 in the arm 79 is large enough to allow play up and down of the lever on its pivot 103. The head of the screw 105 serves as a stop to limit the upward play of the arm. The arm 79 bends down from the 20 carriage-rail, on which it is mounted, to a point substantially opposite the slot formed by the cushions 80, whence, like the carriage-release-lever, it is offset horizontally outward through the cushions to its 25 finger-piece 106. The up-and-down play of the carriage-return-arm is indicated by the dotted lines in Figure 9.

For providing an up-and-down play of the line-space-lever, the bearing thereof on 30 its pivot-pin 76 is rounded off at 107 (see Figure 7), above and below the medial line, after the fashion indicated in Figure 10, in connection with the description of the carriage-release-lever. As indicated in Figures 35 6 and 7, however, the rounding or tapering 107 of the bearing of the line-space-handle, as well as that of the carriage-release-lever 92, is only in a fore-and-aft direction; in the longitudinal cross-section shown in Figure 40 6, no such rounding of the bearing is shown. Figure 5 illustrates the selected shape of the bearing-hole 108 for the line-space-lever. In this figure, the pin-hole at its top and bottom is shown as oblong, having rounded 45 forward and rear ends and flattened sides. Thus, while the line-space-lever has an up-and-down play on its bearing pin in a vertical plane, it cannot be twisted or rocked laterally. This provision against lateral 50 twist is to insure proper engagement of the arm 77 with the pawl-carrying slide.

It has been noted that the carriage-return-arm and the carriage-release-lever are mounted on the same plate 87 on the carriage front rail. In effect, it is as if the carriage-release-lever was pivoted to the carriage-return-arm. This mounting of the carriage-return-arm and the release-lever enables the operator to engage the carriage- 55 return-arm finger-piece 106 with his thumb, and, at the same time, to engage the finger-piece 93 on the release-lever with his forefinger. While thus engaging the finger-piece 106 of the carriage-return-arm, the release-lever is pressed toward the carriage- 60

return-arm, to release the carriage; and the carriage, being so held released, is returned by the thumb which engages the finger-piece 106. When the finger-pieces 93 and 106 are thus seized, the natural position for the 70 thumb is a horizontal position, and the natural position of the forefinger, which bears upon the carriage-release-lever, is a vertical position; otherwise the hand must be twisted. Best to adapt the finger-pieces for such 75 operation, the finger-piece 106 of the carriage-return-arm (see Figure 9) is shown as vertically disposed; and, as indicated in Figure 8, may have a suitable curvature on the left-hand side thereof. For best adaptation of the finger-piece 93 of the release-lever to the vertical position of the forefinger, the finger-piece 93 (see Figures 1 and 8) is horizontally disposed, and may be 80 suitably curved as at 109. In other words, 85 just as the thumb and forefinger are naturally at right angles to each other, so, in the drawings are the finger-pieces 93 and 106 shown at right angles to each other.

Variations may be resorted to within the 90 scope of the invention, and portions of the improvements may be used without others.

Having thus described my invention, I claim:

1. A sound-deadening casing for a type-writing machine, having a work-observation window-pane mounted for adjustment to avoid objectionable reflection of light, and means keeping the window-pane closed at 95 all adjustments, whereby said window-pane, irrespective of its adjustment, co-operates with the casing to confine sounds accompanying the operation of the typewriter.

2. A sound-deadening casing for a type-writing machine, comprising a work-observing window-pane angularly adjustable to deflect objectionable light rays from the line of vision of an operator viewing the work, and means for maintaining a sound-proof seal at the periphery of said window-pane 100 to keep the window closed when adjusted to its several different positions.

3. A sound-deadening casing for a type-writing machine, comprising an opening in the casing, a work-observing window-pane adjustable in said opening to deflect light rays from an operator's line of vision when viewing work in the machine, and sound-deadening means co-operating with both the window-pane and the periphery of said 110 opening to maintain a sound-proof seal to keep the window closed throughout the entire movement of said window-pane to adjusted position.

4. A sound-deadening casing for a type-writing machine, comprising a window-frame, a work-observing window-pane adjustable in said frame to deflect objectionable rays of light from the line of vision of an operator when viewing the work, and 120 125 130

- sound-deadening means lining the periphery of said window-frame, and co-operating with the periphery of said window-pane throughout its entire adjustable movement, 5 to maintain a sound-proof seal between said window-frame and window-pane and thereby keep the window constantly closed.
5. In a sound-deadening casing for a typewriting machine, a window-frame, and 10 a non-opening work-observing window-pane angularly adjustable therein to avoid objectionable reflection of light, the frame being extended in depth to permit substantial angular adjustment of the pane without opening the window.
6. In a sound-deadening casing for a typewriting machine, a window-frame, an observation-window-pane angularly adjustable therein to avoid objectionable reflection of 20 light, the frame being of a depth to permit angular adjustment of the pane without causing the edges of the pane to protrude from the frame, and a yieldable sound-deadening lining for the window-frame, against 25 which lining the edges of the pane are adapted to bear, in the several adjustments thereof.
7. In a sound-deadening casing for a typewriting machine, a window-frame, an observation-window-pane angularly adjustable therein to avoid objectionable reflection of light, the frame being of a depth to permit angular adjustment of the pane without causing the edges of the pane to protrude 30 from the frame, and a yieldable sound-deadening lining for the window-frame, against which lining the edges of the pane are adapted to bear, in the several adjustments thereof, the edges of the pane being rounded 35 or tapered, to allow the same to be pressed into, and moved along, the lining as the pane is adjusted.
8. In a sound-deadening casing for a typewriting machine, a window-frame, a work-observing window-pane angularly adjustable in the window-frame while remaining closed to avoid objectionable reflection of light, and means, including strips set in the frame, for holding the closed pane in the 40 various angular adjustments.
9. In a typewriting machine, a forwardly-extending line-space lever, and a bearing on which the lever is pivoted to have horizontal line-space movement, the engaging portions 45 of the lever and bearing being so constructed that the lever has play in a forwardly and rearwardly extending vertical plane, and is held against play in a vertical plane perpendicular to the first.
10. In a typewriting machine, a vertical pin and a forwardly-extending line-space lever having a bearing on said pin, the bore of said bearing being rounded or tapered in opposite directions from front to rear on opposite 50 sides of the horizontal medial plane of the bearing, to provide for pivotal play of said lever in a forwardly and rearwardly extending vertical plane.
11. In a typewriting machine, a carriage-release lever and a mounting for said lever providing for a horizontal release movement, said mounting being so constructed as to permit pivotal movement of the lever in a forwardly and rearwardly extending vertical plane, while preventing lateral rocking of the lever. 70
12. In a typewriting machine, a traveling carriage, a finger-piece extending forwardly from the carriage, and a finger-piece-mounting on the carriage to provide for an operating movement of said finger-piece in a horizontal plane, said mounting being so constructed as to provide for a pivotal movement of said finger-piece in a forwardly and rearwardly extending vertical plane, while preventing lateral rocking movement. 80
13. The combination with a sound-deadening typewriter-casing having a slot extending across the casing, and yieldable slot-sealing means extending along the slot, of a typewriting machine having a carriage, a horizontally-swingable operating finger-piece projecting forwardly through said slot, and a mounting for said finger-piece to provide for automatic adjustment of said finger-piece to the proper height for said slot by permitting a pivotal movement of the finger-piece in a forwardly and rearwardly extending vertical plane, while preventing a lateral rocking of the finger-piece. 90
14. In a typewriting machine, a carriage-return-arm pivoted to have up-and-down play on the carriage, and a headed screw passing loosely through the arm and into the support therefor, the head of the screw serving as a stop to limit and determine the amount of play. 100
15. The combination with a sound-deadening typewriter-casing having a slot extending across the front thereof, of a typewriting machine having a carriage-return arm projecting through said slot, and means for providing play for the arm in a vertical plane, the arm being held against horizontal movement on the carriage. 110
16. In combination, a typewriting machine, a sound-deadening casing in which the machine is held, a carriage-release-lever pivoted to swing in a horizontal plane on the carriage, a slot in the casing through which the lever protrudes, and along which the lever moves as the carriage moves in the casing, and means to provide play for the lever in a vertical plane, so that the lever may accommodate itself to the position of the slot. 120
17. In combination, a typewriting machine, a sound-deadening casing in which the machine is held, a line-space-lever, a carriage-release-lever, and a carriage-return 130

- arm, all mounted on the carriage, the casing having a slot through which said levers and arm protrude, and along which the same move with the carriage in the casing, and means providing play for said levers and arm in a vertical plane, whereby the same are all brought into registry and accommodate themselves to the position of the slot.
18. In a typewriting machine, a carriage-return-arm having a finger-piece vertically disposed thereon, for engagement by the thumb, and a carriage-release-lever having a finger-piece horizontally disposed thereon, for engagement by the forefinger.
19. In a typewriting machine, a carriage-return-arm having a finger-piece vertically disposed thereon, for engagement by the thumb, and a carriage-release-lever having a finger-piece horizontally disposed thereon, for engagement by the forefinger, the release-lever being pivoted to the carriage-return-arm.
20. In a typewriting machine, a carriage-
- return-arm having a finger-piece vertically disposed thereon, for engagement by the thumb, and a carriage-release-lever having a finger-piece horizontally disposed thereon, for engagement by the forefinger, the release-lever and return-arm being adjacently located, so that they can be pinched together by one hand.
21. A sound-deadening casing for a typewriting machine, said casing and machine being mounted on a drop leaf of a desk, said casing having two sections, namely, a body-part and a cover-part hinged to said body-part, and a bolt on one of said sections, said bolt being movable to a permanent effective position and a permanent ineffective position, said bolt connecting both sections to prevent the opening of the cover-part when the bolt is in its effective position to keep the cover-part closed when the drop leaf is swung into the desk with the machine and the casing.

JOHN WALDHEIM.
